UNITED STATES PATENT OFFICE.

GRANVILLE HUTCHINSON, OF TROY, NEW YORK.

ASSEMBLER-CLUTCH MECHANISM FOR LINE-CASTING MACHINES.

1,179,724.

Specification of Letters Patent. Patented Apr. 18, 1916.

Application filed April 3, 1914. Serial No. 829,226.

To all whom it may concern:

Be it known that I, GRANVILLE HUTCHINSON, a citizen of the United States, residing at Troy, county of Rensselaer, and State of New York, have invented certain new and useful Improvements in Assembler-Clutch Mechanism for Line-Casting Machines, of which the following is a specification.

The invention relates to such improvements and consists in the novel construction and combination of parts hereinafter described and subsequently claimed.

Reference may be had to the accompanying drawings, and the reference characters marked thereon, which form a part of this specification. Similar characters refer to similar parts in the several figures therein.

Figure 1 of the drawings is a view in front elevation of a broken-away part of a line-casting machine showing the assembler-mechanism to which my invention more particularly relates. Fig. 2 is a view in rear elevation of the assembler-plate and mechanism mounted thereon detached from the rest of the machine. Fig. 3 is a vertical longitudinal section taken on the broken line 3—3 in Fig. 2 through the axis of the assembler-belt-driving shaft. Fig. 4 is a horizontal longitudinal section of the same taken on the broken line 4—4 in Fig. 2 through the axis of the assembler-belt-driving shaft, partly broken away and showing only parts which are in rear of the assembler-plate.

In the operation of line-casting machines, trouble is at times experienced due to the matrices becoming clogged or jammed in the assembler, so that the assembler star-wheel cannot feed them out from the assembler. When this occurs, it is necessary to stop the operation of the assembler, while the operator removes the accumulated matrices.

The principal objects of the invention are to prevent jamming the matrices in the assembler and to enable the operator to easily, quickly and safely stop and start the assembler-mechanism at will.

Referring to the drawings wherein the invention is shown in preferred form, 1 is the assembler-belt upon which matrices are deposited by the feed-chutes, 2. The assembler-mechanism is mounted upon a plate, 3, termed the assembler-plate, which plate is attached by screws, 4, to the body or frame, 5, of the machine. The assembler-belt, 1, is driven by a pulley, 6, over which the belt passes, which pulley is fixed upon a sleeve, 7,

rotatively mounted in a bearing in the assembler-plate, 3. The assembler-belt-driving pulley, 6, is thus fixed upon the sleeve, 7, in front of the assembler-plate, 3, and a pinion, 8, is fixed upon said sleeve in rear of the assembler-plate, which pinion serves to drive the assembler-star-wheel-pinion, 9, through the medium of an intermediate gear, 10. The assembler-star-wheel-pinion, 9, is fixed upon the star-wheel-shaft, 11, which carries the assembler-star-wheel, 12.

The rear end of the sleeve, 7, is formed with an enlargement or head, 13; and a belt-driven pulley, 14, is rotatively mounted upon the sleeve, 7, between the head, 13, thereof and the pinion, 8, in rear of the plate, 3. The web of the driven pulley, 14, has formed upon its rear side a pair of clutch-members in the form of lugs or abutments, 15. A shaft, 16, is mounted to reciprocate longitudinally within the sleeve, 7, while caused to rotate therewith by means of a T-head, 17 on the shaft, which is adapted to play in a transverse slot, 18, formed in the head, 13, of the sleeve. The ends of the T-head, 17, project beyond the head, 13, of the sleeve and form clutch-members engageable with the clutch-members, 15, on the driven pulley, 14, when the shaft, 16, is drawn toward the front of the machine, as indicated by dotted lines in Fig. 3. When said members are so engaged, the sleeve, 7, pinion, 8, and assembler-belt-driving pulley, 6, are caused to rotate in unison with the belt-driven pulley, 14, which is continuously driven by the belt 31. By rearward movement of the shaft, 7, the T-head 17, can be disengaged from the clutch-members, 15, of the pulley, 14, as shown in Fig. 4, permitting the pulley, 14, to run as an idle pulley, and stopping the operation of the sleeve, 7, and the assembler-mechanism connected therewith, and also stopping the operation of the star-wheel 12. A hand-wheel, 19, is loosely mounted upon the front end of the shaft, 16, between a head, 20, on the front end of the shaft and a nut, 21, fitting a screw-threaded portion of the shaft. The hand-wheel, 19, can thus be safely grasped by the operator, while the assembler is in operation, and the operator can, without danger, reciprocate the shaft, 16, in disconnecting and connecting the assembler-belt-driving mechanism and star-wheel-driving mechanism with the driven-pulley, 14. To prevent an accidental rearward movement of

the shaft, 16, I provide the head, 13, of the sleeve, 7, with a radial aperture, 22, and locate therewithin a spring-actuated ball-detent, 23, adapted to frictionally engage a notch or recess, 24, formed in the shaft, 16, or the T-head thereof, when the shaft, 16, is in its forward position.

In carrying out my invention, as above described, the assembler-mechanism can be 10 quickly stopped or started by the operator without danger of injury, because the clutch-mechanism is located wholly in rear of the assembler-plate, 3, and the handle or hand-wheel, 19, whereby the clutch is operated, 15 is not a part of the driving or driven mechanism.

My invention makes it possible for the operator of the machine, at the first indication of the failure of the assembler-belt 20 and star-wheel to properly feed the matrices through the assembler, to immediately stop the operation of the star-wheel to prevent jamming the matrices already delivered to the assembler by the assembler-belt, 25 and the delivery of other matrices which would tend to further clog the assembler.

What I claim as new and desire to secure by Letters Patent is—

1. In a machine of the class described, the 30 combination with a supporting-plate; of a sleeve rotatively mounted upon said plate; a driven-pulley rotatively mounted upon said sleeve; a driving-pulley fixed upon said sleeve; a driving-pinion fixed upon said 35 sleeve; a shaft reciprocatory longitudinally within said sleeve and adapted to rotate therewith; a handle on the front end of said shaft; a clutch on the rear end of said shaft adapted to be moved into and out of engagement with said driven-pulley by longitudinal movement of said shaft; a feed-belt passing over said driving-pulley; a star-wheel rotatively mounted in position to receive and feed matrices delivered by said belt, and 40 driving-connections between said pinion and said star-wheel.

Copies of this patent may be obtained for five cents each, by addressing the "Commissioner of Patents, Washington, D. C."

2. In a machine of the class described, the combination with a supporting-plate; of a sleeve rotatively mounted upon said plate; a driven-pulley rotatively mounted upon 50 said sleeve; a driving-pulley fixed upon said sleeve; a driving-pinion fixed upon said sleeve; a shaft reciprocatory longitudinally within said sleeve and adapted to rotate therewith; a handle rotatively mounted on 55 the front end of said shaft; a clutch on the rear end of said shaft adapted to be moved into and out of engagement with said driven-pulley by longitudinal movement of said shaft; a feed-belt passing over said 60 driving-pulley; a star-wheel rotatively mounted in position to receive and feed matrices delivered by said belt; and driving-connections between said pinion and said star-wheel. 65

3. In a machine of the class described, the combination with a supporting plate; of a sleeve rotatively mounted upon said plate; a driven-pulley rotatively mounted upon 70 said sleeve; a driving-pulley fixed upon said sleeve; a driving-pinion fixed upon said sleeve; a shaft reciprocatory longitudinally within said sleeve and adapted to rotate therewith; a handle on the front end of said shaft; a clutch on the rear end of said shaft 75 adapted to be moved into and out of engagement with said driven-pulley by longitudinal movement of said shaft; a feed-belt passing over said driving-pulley; a star-wheel rotatively mounted in position to receive and feed matrices delivered by said belt; driving-connections between said 80 pinion and said star-wheel; and a spring-actuated ball-detent carried by said sleeve, said shaft being recessed to receive said ball-detent. 85

In testimony whereof I have hereunto set my hand this 27 day of March, 1914.

GRANVILLE HUTCHINSON.
